Cecil M. Clarke

By Frank D. Thomas, Atty

UNITED STATES PATENT OFFICE.

CECIL M. CLARKE, OF CHICAGO, ILLINOIS.

DIPPING-VAT FOR BUILDING-PAPER, &c.

1,381,967.

Specification of Letters Patent. Patented June 21, 1921.

Application filed October 7, 1920. Serial No. 415,238.

To all whom it may concern:

Be it known that I, CECIL M. CLARKE, a citizen of the United States, residing at Chicago, in the county of Cook and State of Illinois, have invented new and useful Improvements in Dipping-Vats for Building-Paper, &c., of which the following is a full, clear, and exact description.

Heretofore this has been done in an apparatus employing a vat or tank by drawing the paper through the liquid in a comparatively straight course or over and under staggered rolls. The length of the paper being immersed was necessarily limited to the length of the course it followed, and the period of saturation was limited to the length of time it took to travel such course. As the output of the apparatus depended upon the speed at which the saturation could take place, the paper was drawn through the vat as fast as possible and subjected to such a strain that it frequently broke and caused considerable delay and expense.

My improvements are designed to saturate a much greater length of paper in vats of the same liquid capacity as those heretofore used to subject the paper to a more thorough saturation for a longer period of time, and to discharge said saturated paper at a very much greater speed than was heretofore possible without subjecting the same to any strain and the delays and expense resulting from the breakage of said paper. This I accomplish by the means hereinafter fully described and as particularly pointed out in the claims.

In the drawings:

Figure 1 is a longitudinal vertical section of a vat, showing my improvements applied thereto.

Fig. 2 is a plan view of the same.

In the drawings, 5, represents a comparatively long vat which is of a suitable depth and is of a width sufficiently greater than the width of the paper 6 threaded through the same so as to provide the desired clearance. One end of said vat is provided with brackets, 7, 7, and standards, 8, 8, are supported upon these brackets and have bearings for transverse feed-rollers, 9 and 10. The bearings of the lower feed-roller are stationary, but the bearings of the upper roller consist of blocks (not shown) that are adjustable up and down in the vertically elongated slots 11 in said

standards by means of screws 12 whose upper ends are provided with hand-wheels with which to turn them.

The web of paper 6 is passed between rollers 9 and 10, thence pass forward over an idle-roller 14 and then down into the vat, 60 where it is immersed and engaged by and carried to the opposite end of the tank in a series of loops or festoons by a suitable conveyer, as indicated by the arrow in Fig. 2 of the drawings. This conveyer consists of 65 two corresponding endless chains 15, 15, near and parallel to the inner surface of each side of the vat, and these chains are mounted upon and engaged by sprocket-wheels 16, 17, 18, and 19 that are mounted on and revolve with 70 transverse shafts 16^a, 17^a, 18^a, and 19^a, respectively. Two of these shafts are situated near the top of the vat at such an altitude that the sprockets thereon and the upper stretches of the chains, 15, will be wholly immersed in and below the surface of the liquid, and the other two sprocket-wheels 18^a and 19^a are located below the same near the bottom of the vat. All of these shafts are journaled in the sides of the vat, and one, preferably shaft 16^a, has one end extending through its bearing and a sprocket-wheel 20 securely mounted thereon. Sprocket-wheel 20 is connected to a sprocket-wheel 35 securely mounted on the extended end of the 85 journal of roller 9 through the medium of which it derives motion.

The conveyer chains 15 are connected by a series of transverse bars 21, 21, that are, preferably, separated an equal distance 90 apart, say every twelve inches. When the machine is in operation the upper stretch of said chains move at a comparatively slow speed toward the end of the vat opposite the feed-rollers. When the bars 21 arrive in 95 succession at a point immediately over the shaft 16^a the paper between said bar and the bar preceding it is pushed downward to form a loop or festoon by a downwardly plunging roller 22.

At the instant this roller 22 plunges downward, the bend of the paper hung on said "preceding" bar 21 will be engaged by a transverse roller 23 the weight of which is such that it will prevent the rearward movement or slipping of the paper at the time the loop is being formed. Roller 23 is journaled in the ends of arms 24, 24, securely mounted

on transverse studs 25 projecting from the sides of the vat, and the downward movement of said roller is limited by stop-pins 26 projecting from the sides of the tank and are 5 engaged by said arms 24, when the roller has moved downward sufficiently.

The plunger-roller 22 is journaled in the lower ends of the bifurcated branches of a pendent plunger 27, whose upper end is pivotally mounted upon a wrist-pin 28 connecting corresponding opposing wheels 29, 29. These wheels are mounted upon the adjacent ends of axially alining separated sections of a transverse shaft 30, the outer ends of 15 which are journaled in bearings in the upper ends of uprights 31, 31, which latter have their bases supported upon and secured to the sides of the vat. Near the bearing of the outer end of one of the sections of shaft 20 30 it has a sprocket-wheel 32 securely mounted thereon and this sprocket is connected by an endless chain 33, to a sprocket-wheel 34 mounted on shaft 16^a alongside of sprocket-wheel 16 within the tank.

25 The connecting of the shafts on which the sprocket-wheels 35, 20, 32, are mounted enables the making and assembling of these parts so that their relative movements and action can be timed to accomplish the objects 30 of my improved apparatus as hereinbefore set forth, and to enable the conveyer to carry the series of corresponding loops of paper to the discharge end of the tank where the paper is removed. When the advanced bar 35 21 of the most advanced loop arrives at a point immediately over shaft 17^a, a pair of withdrawal-rollers, 36 and 37 to and between which the paper passes, draws said paper forward and takes up the said loop 40 while the chains 15 are moving forward a distance corresponding to that between said bars 21.

Rollers 36 and 37 are journaled in standards 39, 39, whose bases rest upon and are 45 secured to the platforms of brackets 40, secured to the outer side of the discharge end of the vat. The lower discharge-roller 36 has stationary bearing but the bearings of the upper roller are adjustable in vertically 50 elongated slots 41 in said standards by means of screws 42. The feed-rollers and the discharge-rollers revolve at the same speed, the latter taking their motion from the shaft 17^a through the medium of 55 sprocket-wheel 43 mounted on the extended end of said shaft 17^a and sprocket-wheel 44, on the extended end of the journal of the upper discharge-roller 37, and chain 45.

In order to provide the necessary length 60 of paper to enable the first loop to be made with pulling, the feed-rollers are revolved at such a speed that the slack for the first loop within the vat is accumulated between the front end of the vat and the feed-rollers 65 for the first loop, substantially as shown in

dotted lines in Fig. 2 of the drawings. This is the preferred way of supplying the necessary length of paper for the construction of the loops, but, while it is not deemed as satisfactory, the paper may run from the feed-rollers direct to the first guide-roller.

What I claim as new is:

1. In combination, a vat, a conveyer in said vat having a plurality of individual members adapted to receive each the individual loop of a looped web, and means for feeding said web to and from the vat.

2. An apparatus of the kind specified comprising a vat, and a conveyer having members adapted to carry a continuous web of paper in individually spaced loops longitudinally through the same.

3. An apparatus of the kind specified comprising a vat, means for feeding a continuous web of paper to said vat and a conveyer having separate members adapted to carry said web in individual loops through the same.

4. An apparatus of the kind specified comprising a vat, rollers for feeding a continuous web of paper to said vat, rollers for withdrawing said web from the same, and a conveyer having individual members adapted to carry the web in individual loops through said vat.

5. An apparatus of the kind specified comprising a vat, rollers for feeding a continuous web of paper to said vat, in a rectilinear path, rollers for withdrawing said web from the same, a conveyer adapted to receive said web from said feed-rollers and convey the same to said withdrawal rollers, and means for diverting the web from its rectilinear path for looping said web as it is received by said conveyer.

6. An apparatus of the kind specified comprising a vat, and a conveyer within said vat adapted to carry a continuous web of paper in loops through the same and consisting of corresponding endless chains that travel in a rectangular course, sprocket-wheels therefor at the angles of said course, and transverse bars connecting said chains and separated at suitable intervals apart.

7. An apparatus of the kind specified comprising a vat, and a conveyer within said vat adapted to carry a continuous web of paper in loops through the same and consisting of corresponding endless chains that travel in a rectangular course, sprocket-wheels therefor at the angles of said course, and equi-distant transverse bars connecting said chains.

8. An apparatus of the kind specified comprising a vat, and a conveyer within said vat adapted to carry a continuous web of paper in loops through the same and consisting of corresponding endless chains that travel in rectangular course, sprocket-wheels therefor at the angles of said course, trans-

verse bars connecting said chains, and means for forming depending loops while said conveyer is in operation.

9. An apparatus of the kind specified comprising a vat, and a conveyer within said vat adapted to carry a continuous web of paper in loops through the same and consisting of corresponding endless chains that travel in rectangular course, sprocket-wheels therefor at the angles of said course, transverse bars connecting said chains, and a transverse roller for forming depending loops while said conveyer is in operation.

10. An apparatus of the kind specified comprising a vat, and a conveyer within said vat adapted to carry a continuous web of paper in loops through the same and consisting of corresponding endless chains that travel in a rectangular course, sprocket-wheels therefor at the angles of said course, transverse bars connecting said chains, a transverse roller for forming depending loops while said conveyer is in operation, and a vertically movable depending plunger in the lower ends of the bifurcations of which said last mentioned roller is journaled.

11. An apparatus of the kind specified comprising a vat, and a conveyer within said vat adapted to carry a continuous web of paper in loops through the same and consisting of corresponding endless chains that travel in rectangular course, sprocket-wheels therefor at the angles of said course, transverse bars connecting said chains, a transverse roller for forming depending loops while said conveyer is in operation, a vertically movable depending plunger in the lower ends of the bifurcations of which said last mentioned roller is journaled, disks between which the upper end of said plunger is pivoted, and a transverse shaft having two alining sections to the separated opposing ends of which said disks are secured.

12. An apparatus of the kind specified comprising a vat, feed-rollers that supply a continuous web of paper thereto, withdrawal-rollers that withdraw said web therefrom, and a conveyer within said vat adapted to receive the web from the feed-rollers and carry the same in loops to said withdrawal-rollers, said conveyer consisting of corresponding endless chains that travel in a rectangular course, sprocket-wheels therefor at the angles of said course, and transverse bars upon which said loops are hung connecting said chains and separated at suitable intervals apart.

13. An apparatus of the kind specified comprising a vat, feed-rollers that supply a continuous web of paper thereto, withdrawal rollers that withdraw said web therefrom, a conveyer within said vat adapted to receive the web from the feed rollers and carry the same in loops to said withdrawal-

rollers, said conveyer consisting of corresponding endless chains that travel in a rectangular course, sprocket-wheels therefor at the angles of said course, and transverse bars upon which said loops are hung connecting said chains and separated at suitable intervals apart, and means for forming said loops while said conveyer is in operation.

14. An apparatus of the kind specified comprising a vat, feed-rollers that supply a continuous web of paper thereto, withdrawal-rollers that withdraw said web therefrom, a conveyer within said vat adapted to receive the web from the feed-rollers and carry the same in loops to said withdrawal-rollers which consists of corresponding endless chains that travel in a rectangular course, sprocket-wheels therefor at the angles of said course, and transverse bars upon which said loops are hung connecting said chains and separated at suitable intervals apart, and a roller for forming said loops while said conveyer is in operation.

15. An apparatus of the kind specified comprising a vat, feed-rollers that supply a continuous web of paper thereto, withdrawal-rollers that withdraw said web therefrom, a conveyer within said vat adapted to receive the web from the feed-rollers and carry the same in loops to said withdrawal-rollers which consists of corresponding endless chains that travel in a rectangular course, sprocket-wheels therefor at the angles of said course and transverse bars upon which said loops are hung connecting said chains and separated suitable intervals apart, a transverse roller for forming said loops while said conveyer is in operation and a vertically movable depending plunger in the lower ends of the bifurcations of which said last mentioned roller is journaled.

16. An apparatus of the kind specified comprising a vat, feed-rollers that supply a continuous web of paper thereto, withdrawal-rollers that withdraw said web therefrom, and a conveyer within said vat adapted to receive the web from the feed-rollers and carry the same in loops to said withdrawal rollers which consists of corresponding endless chains that travel in a rectangular course, sprocket-wheels therefor at the angles of said course and transverse bars upon which said loops are hung connecting said chains and separated at suitable intervals apart, and a transverse roller for forming said loops while said conveyer is in operation, a vertically movable depending plunger in the lower ends of the bifurcations of which said last mentioned roller is journaled, disks between which the upper end of said plunger is pivoted, and a transverse shaft having two alining sections to the separated ends of which said disks are secured.

17. An apparatus of the kind specified comprising a vat, and a conveyer within said vat adapted to carry a continuous web of paper in loops through the same and consisting of corresponding endless chains that travel in rectangular course, sprocket-wheels therefor at the angles of said course, transverse bars connecting said chains, means for forming depending loops while said conveyer is in operation and a device for preventing the rearward movement of said web. 30
18. An apparatus of the kind specified comprising a vat, and a conveyer within said vat adapted to carry a continuous web of paper in loops through the same and consisting of corresponding endless chains that travel in rectangular course, sprocket-wheels therefor at the angles of said course, transverse bars connecting said chains, means for forming depending loops while said conveyer is in operation and a transverse roller that bears down upon the second transverse bar from the receiving end of the vat while the loop is being formed between the same and the first bar. 35
19. In combination, a vat, a conveyer in
20. In combination, a vat, a conveyer in said vat, provided with individual spaced members, means for feeding a web to said conveyer at a greater speed than that of the conveyer, and means for forming a plurality of loops successively in said web for reception upon said members. 40
21. In combination, a vat, a conveyer in said vat, provided with individual spaced members, means for feeding a web to said conveyer at a greater speed than that of the conveyer, and means engaging the web upon entrance of the same to the vat for forming successively a plurality of loops in said web for reception individually upon said members. 45

In witness whereof I have hereunto set my hand this 30th day of September, 1920.

CECIL M. CLARKE.
